UNITED STATES PATENT OFFICE.

MARGUERITE CONNELL, OF NEW YORK, N. Y.

COLLAR-SUPPORTER.

No. 820,767.

Specification of Letters Patent.

Patented May 15, 1906.

Application filed June 1, 1905. Serial No. 263,260.

To all whom it may concern:

Be it known that I, MARGUERITE CONNELL, a citizen of the United States, and a resident of the city of New York, borough of Manhattan, in the county and State of New York, have invented a new and Improved Collar-Supporter, of which the following is a full, clear, and exact description.

The purpose of my invention is to provide a supporter for lace collars or collars made from thin material, which supporter is exceedingly simple and economic of construction and capable of being expeditiously and conveniently applied to the collar or removed when the collar is to be washed, for example.

Another purpose of the invention is to provide a supporter which will hold the most flimsy collar in an upright position, but which will not cause discomfort to the wearer, injure the collar, or be visible when the collar is worn, even though considerable open-work is a feature of the collar.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is an inner face view of a collar and applied supporter. Fig. 2 is an enlarged transverse section taken practically on the line 2 2 of Fig. 1. Fig. 3 is a transverse section through the cap and supporter on the line 3 3 of Fig. 2, and Fig. 4 is a detail perspective view of one of the supporting-stays.

A represents a collar of the standing type and which is made of a light material not capable of being self-sustaining when worn.

B represents caps which are permanently secured to the collar, and C represents sustaining or supporting stays. The caps B are preferably made of linen or other stout material and are each complete in itself, each cap consisting of two side pieces 10 and 11, rounded at one end. The two said side pieces 10 and 11 are connected at their longitudinal edges and at their rounded ends by stitching 12 or other suitable means, and the opposite end portion of the cap is left open, as is shown at 13 in the drawings. Series of the caps B are secured to the inner face of the

collar A, one series near the top of the collar and the other series near the bottom, as near to the said points as practicable.

Opposing caps B are adapted to receive the end portions of the sustaining or supporting stays C above referred to. These stays C are made of a flexible material and their ends 14 are rounded off so as to fit into the rounded closed end portions of the caps B, and under this construction the ends of the stays are prevented from cutting their way out through the closed ends of the caps. These stays are made of a transparent material, such as celluloid, which material is preferred, and they are thus made transparent in order that when the collar is worn the flesh tint will show through the stays as well as through any open-work in the collar behind which they may cross. The supporters are placed mainly transversely of the collar, but ordinarily the central stays or the stays at each side of the center of the collar are given an inclination from the top downward in direction of the lower central portion of the collar, as is illustrated in Fig. 1. The arrangement of the stays, however, depends largely upon the shape of the collar. These caps are secured to the collar by stitching, and consequently when the stays are removed from the caps the collar may be washed, and it is evident the stays may again be placed readily in position when required.

The improved supporting devices are exceedingly light and are effective, holding the collar in an upright position, and by reason of their elasticity the collar will yield when the head is thrown back or to one side, returning again to position when the head of the person is brought to normal place.

Having thus described my invention, I claim as new and desire to secure by Letters Patent—

1. A lace or like collar provided on its inner face with opposing pockets and flexible transparent stays, the ends of which enter said pockets.
2. A lace or like collar provided on its inner face adjacent to its upper and lower edges with a plurality of opposing pockets of fibrous material, and flexible transparent stays having their ends in the said pockets.
3. A collar of lace or like flimsy material provided with a plurality of pockets adjacent

to the top and bottom edges of the collar, and
a plurality of flexible stays having their ends
entering said pockets, the stay at each side of
the center of the collar being given an incli-
5 nation from the top downward in direction of
the lower central portion of the collar.

In testimony whereof I have signed my

name to this specification in the presence of
two subscribing witnesses.

MARGUERITE CONNELL.
